HEAT EXCHANGE SYSTEM FOR VAPOR GENERATORS

Julius H. Bayard, New York, N. Y., assignor to Foster Wheeler Corporation, New York, N. Y., a corporation of New York

Application July 3, 1953, Serial No. 365,928

6 Claims. (Cl. 122—1)

This invention relates to heat exchange apparatus and more particularly to a preheater system for a vapor generator.

It is usual in vapor generators to heat feed water therefor in an economizer positioned in heat exchange relationship with gases from the furnace of the vapor generator which, in turn, lowers the temperature of said gases. If the temperature of the feed water entering the economizer is of such degree that the heat removed from the gases does not lower the gas temperature to the desired degree an air heater is positioned in heat exchange relationship with gases beyond the economizer in the direction of flow of the gases. Since the specific heat of the exhaust gases in relationship to the air is low, the size of the air heater is normally very large.

In accordance with the present invention a portion of the feed liquid from a feed pump is passed to the inlet of the lower section of an economizer having a lower, middle and upper section. Another portion is passed to the middle section of the economizer. The middle section of the economizer is located beyond the lower section of the economizer in the direction of flow of combustion gases from the furnace so that said gases pass in heat exchange relationship with said lower section, prior to passing in heat exchange relationship with said middle section. The upper section of the economizer is located beyond the middle section of the economizer in the direction of flow of combustion gases from the furnace so that said gases pass in heat exchange relationship with said middle section, prior to passing in heat exchange relationship with said upper section. The feed liquid passing through said lower and middle sections of the economizer is heated by passing in indirect heat exchange relationship with gases of combustion flowing from the furnace, the portion of feed liquid in the lower section of the economizer being heated to a higher temperature than the portion of feed liquid flowing through the middle section of the economizer. This is due to the greater mean temperature difference between the hot exit gases passing in heat exchange relationship with the relatively cool feed liquid flowing through the lower section, than the temperature difference between the exit gases which have already given up some of their heat, thereafter passing in heat exchange relationship with the other portion of relatively cool feed liquid in the middle section.

The relatively hot feed liquid thereafter flows out of the outlet of the lower economizer section to the inlet of an air heater. Here the feed liquid is passed in indirect heat exchange relationship with cold air to be used to support combustion in the furnace of a vapor generator thereby decreasing the temperature of said feed liquid and heating the air to a relatively hot temperature. Since the mean temperature difference between the air and feed liquid is large, the air heater provided can be small and the air can be heated to a high temperature therein. The heated air is thereafter passed to the vapor generator to support combustion and the relatively cool feed is passed out of the outlet of the air heater to the inlet of the

2

upper section of the economizer. The feed liquid flowing through said upper section regains part of the heat given up to the air by passing in indirect heat exchange relationship with relatively cool gases of combustion flowing from the furnace of the vapor generator. These gases are relatively cool since some of their heat content has been given up by being previously passed in indirect heat exchange relationship with the liquid flowing through the lower and middle sections of the economizer, as hereinbefore described. The feed liquid thereafter flows to the outlet of said upper economizer section and joins the portion of feed liquid flowing to the inlet of the middle section of the economizer further regaining heat given up to the air, by passing in indirect heat exchange relationship with gases of combustion flowing from the furnace, as hereinbefore described. All of the feed liquid then leaves the outlet of said middle section and flows to the feed liquid inlet of the vapor generator.

The present invention provides apparatus for preheating feed water and preheating air for a vapor generator in which the temperature of the flue gases of a vapor generator may be controlled and in which expansion tanks and the like are not necessary.

This invention also provides apparatus for preheating air and feed water for a vapor generator in which separate feed water pumps are not required and in which the possibility of air heater fires are greatly reduced and in which the air heater may be positioned in any desired location.

30 The invention will be understood from the following description when considered in connection with the accompanying drawing forming a part thereof and in which the single figure is a somewhat diagrammatic transverse vertical section of the apparatus of the present invention.

35 Referring to the drawing, the apparatus of the present invention is disclosed as embodied in a vapor generator comprising a setting 10 having vapor generating surface therein with an upper steam and water drum 11 associated therewith together with a lower water drum 12 in the lower part of the setting in substantial vertical alignment with said upper drum. Drums 11 and 12 are connected by a substantially vertical bank of steam generating tubes 13 having a central baffle 14 extending from said lower drum upwardly to a point short of the upper drum. At one side of the bank of tubes 13 is a furnace or combustion chamber 15 fired, as shown, by a plurality of burners 16. The roof and side wall of chamber 15 is lined by water tubes 17. At the opposite side of bank 13 is a gas outlet passage 18 which communicates with gas inlet 19 of flue or stack 20. The flue has a gas outlet 21 which acts as a gas outlet for the setting.

An economizer 22 having an upper section 23 with a feed water inlet 24 and a feed water outlet 25 is positioned in flue 20. Economizer 22 has a middle section 26 over which gases from gas passage 18 pass prior to flowing in heat exchange relationship with upper section 23. Middle section 26 of the economizer has a feed water inlet 27 and a feed water outlet 28. Feed water outlet 28 is in communication with the water space of drum 11 through a conduit 29. A lower section 30 is also provided for economizer 22 over which gases from gas passage 18 pass prior to flowing in heat exchange relationship with middle section 26. Lower section 30 has a feed water inlet 31 and a feed water outlet 32.

65 As shown, feed water to be used in the vapor generator, which feed water may be condensate from a condenser, not illustrated, is discharged by a feed pump 33 through an economizer inlet conduit 34 having one end in communication with said pump and the other end in communication with inlet 31 of lower section 30 of the economizer. A portion of the feed passes into section 30 through its inlet 31, and another portion passes into mid-

the section 26 of the economizer through inlet 27 by conduit 35 which communicates at one end with conduit 34 and at the opposite end with inlet 27. The portion of feed water which enters lower section 30 through inlet 31 flows therethrough and then passes out therefrom by outlet 32 to an air heater 36 by heater inlet conduit 37 having one end in communication with outlet 32 and the opposite end in communication with heater inlet 38.

Air heater 36 comprises a plurality of tubes 39 extending transversely of air conducting means or air conduit 40. Adjacent tubes are connected by return bends 41 and 42 so that feed water entering the air heater through inlet 38 passes in a continuous path of flow from the lower tube to the upper tube thereafter to pass from the heater at outlet 43. As shown, tubes 39 have extended surface members 44 thereon. Air conduit 40 is in communication above air heater 36 with a source of air to be heated and extends below said air heater and into communication with the furnace 15 through burners 16.

Feed water which has passed through air heater 36 flows therefrom through outlet 43 and into upper section 23 of the economizer 22 through heater outlet conduit 45 which communicates at one end with outlet 43 and at the opposite end with inlet 24 of economizer section 23. Feed water which enters section 23 of economizer 22 through inlet 24 flows therethrough and thence into middle section 26 of the economizer through outlet 25 and conduit 46 which communicates at one end with outlet 25 and at the opposite end with conduit 35.

In operation, gases of combustion from combustion chamber 15 flow therefrom into bank of tubes 13 and are directed upwardly by baffle 14 over some of the tubes thence downwardly over the remainder of the tubes and into gas passage 18. From gas passage 18, the gases flow through outlet 19 thence in heat exchange relationship with the tubes of lower economizer section 30, thereafter in heat exchange relationship with the tubes of middle economizer section 26, and thereafter in heat exchange relationship with the tubes of economizer section 23.

Feed water to be heated for the vapor generator passes by feed pump 33 through an economizer inlet conduit 34. A portion of the feed water thereafter passes into lower section 30 of economizer 22 by conduit 34 and another portion passes into middle section 26 of said economizer by conduit 35. The feed water passing into sections 30 and 26 is heated by passing in indirect heat exchange relationship with the combustion gases flowing from the furnace through outlet 19. The portion of feed water passing into the lower section 30 of the economizer is heated to a much higher temperature than the portion of feed water flowing through the middle section since the temperature difference between the gases and feed water is greater.

The relatively hot feed water thereafter flows out of economizer section 30 by conduit 37 to air heater 36 and passes in indirect heat exchange relationship with cold air flowing through air conduit 40 of the heater. Since the mean temperature difference between the cold air passing through the heater and the hot feed water is large, the air can be heated to a high temperature with a small air heater. The heated air then passes to burners 16 to support combustion in the vapor generator and the feed water which is now relatively cool passes to upper section 23 of the economizer by conduit 45. In section 23, the feed water regains part of the heat given up to the air by passing in indirect heat exchange relationship with combustion gases flowing from the furnace which have had their temperature previously reduced by passing in heat exchange relationship with feed water in the lower and middle sections of the economizer. Feed water then flows out of section 23 by conduit 46 and joins feed water flowing into the middle section 26 of the economizer through conduit 35. Here, further passage of the feed water and combustion gases flowing from the furnace chamber in indirect heat exchange relationship with one

another provides an increase in temperature of the feed water and correspondingly decrease in temperature of the exit gases in the stack. The heated feed water thereafter is passed to the steam and water drum 11 of the vapor generator by conduit 29.

Inasmuch as changes may be made in the form, location and relative arrangement of the several parts of the apparatus disclosed without departing from the essential characteristics of the invention, it will be understood that the invention is not to be limited excepting by the scope of the appended claims.

What is claimed is:

1. In a vapor generating apparatus comprising a vapor generator having a setting, a furnace in the setting, means for firing the furnace, said setting having a gas outlet in communication with the furnace and through which gases of combustion flow from the setting, vapor generating surface in the setting in heat exchange relationship with said gases of combustion prior to the flow of said gases from the setting gas outlet, a source of feed liquid, an economizer disposed in said setting beyond said generating surface and in heat exchange relationship with gases of combustion flowing to said gas outlet, said economizer having a plurality of sections disposed in the path of flow of the gases passing to the gas outlet and having liquid from said source flowing therethrough, one of said sections being so disposed in relation with the other sections and with said path of gases of combustion to provide a higher temperature of feed liquid in said one section than in the other sections, an air heater comprising air conducting means through which air flows and a tubular flow path communicating with said one section to receive the feed liquid after passing through said one section to provide flow of liquid through said tubular path, said tubular flow path being disposed in heat exchange relationship with said air conducting means, said air conducting means communicating with said firing means to provide the latter with preheated air, and means communicating the other sections of said economizer with said vapor generator to provide the latter with preheated feed liquid.
2. In a vapor generating apparatus comprising a vapor generator having a setting, a furnace in the setting, means for firing the furnace, said setting having a gas outlet in communication with the furnace and through which gases of combustion flow from the setting, vapor generating surface in the setting in heat exchange relationship with said gases of combustion prior to the flow of said gases from the setting gas outlet, a source of feed liquid, an economizer disposed in said setting beyond said generating surface and in heat exchange relationship with gases of combustion flowing to said gas outlet, said economizer having a first, second, and third section disposed in the path of flow of the gases passing to the gas outlet and having liquid from said source flowing therethrough, the third of said sections being so disposed in relation with the first and second sections and with said path of gases of combustion to provide a higher temperature of feed liquid in said third section than in the first and second sections, the second of said sections being so disposed in relation with said first section and with said path of gases of combustion to provide a higher temperature of feed liquid in said second section than in said first section, an air heater comprising air conducting means through which air flows and a tubular flow path communicating with said third section to receive the feed liquid after passing through said one section to provide flow of liquid through said tubular path, said tubular flow path being disposed in heat exchange relationship with said air conducting means, said air conducting means communicating with said firing means to provide the latter with preheated air, and means communicating the first and second sections of said economizer with said vapor generator to provide the latter with preheated feed liquid.
3. In a vapor generating apparatus comprising a vapor generator having a setting, a furnace in the setting, means

for firing the furnace, said setting having a gas outlet in communication with the furnace and through which gases of combustion flow from the setting, vapor generating surface in the setting in heat exchange relationship with said gases of combustion prior to the flow of said gases from the setting gas outlet, a source of feed liquid, an economizer disposed in said setting beyond said generating surface and in heat exchange relationship with gases of combustion flowing to said gas outlet, said economizer comprising a first, second and third section having liquid from said source flowing therethrough, said first and second sections being disposed beyond said third section in the path of flow of the gases passing to the gas outlet to provide a higher temperature of feed liquid in said third section than in the first and second sections, an air heater comprising air conducting means through which air flows and a tubular flow path communicating with said third section to receive the feed liquid after passing through said one section to provide flow of liquid through said tubular path, said tubular flow path being disposed in heat exchange relationship with said air conducting means, said air conducting means communicating with said firing means to provide the latter with preheated air, and means communicating the first and second sections of said economizer with said vapor generator to provide the latter with preheated feed liquid.

4. In a vapor generating apparatus comprising a vapor generator having a setting, a furnace in the setting, means for firing the furnace, said setting having a gas outlet in communication with the furnace and through which gases of combustion flow from the setting, vapor generating surface in the setting in heat exchange relationship with said gases of combustion prior to the flow of said gases from the setting gas outlet, a source of feed liquid, an economizer disposed in said setting beyond said generating surface and in heat exchange relationship with gases of combustion flowing to said gas outlet, said economizer comprising a first, second, and third section disposed beyond one another respectively in the path of flow of the gases passing to the gas outlet and having liquid from said source flowing therethrough to provide a higher temperature of feed liquid in said third section than in the first and second sections, an air heater comprising air conducting means through which air flows and a tubular flow path communicating with said third section to receive the feed liquid after passing through said one section to provide flow of liquid through said tubular path, said tubular flow path being disposed in heat exchange relationship with said air conducting means, said air conducting means communicating with said firing means to provide the latter with preheated air, and means communicating the first and second sections of said economizer with said vapor generator to provide the latter with preheated feed liquid.

5. In a vapor generating apparatus comprising a vapor generator having a setting, a furnace in the setting, means for firing the furnace, said setting having a gas outlet in communication with the furnace and through which gases of combustion flow from the setting, vapor generating surface in the setting in heat exchange relationship with said gases of combustion prior to the flow of said gases from the setting gas outlet, an economizer disposed in said setting beyond said generating surface in heat exchange relationship with gases of combustion flowing

to said gas outlet, said economizer comprising a first section, a second section, and a third section disposed beyond one another respectively in the path of flow of the gases passing to the gas outlet, said economizer sections each having an inlet through which liquid enters the section and an outlet through which liquid passes from the section after flow therein, means for supplying feed liquid to the inlets of said second and third sections, an air heater comprising air conducting means through which air to be heated flows and a tubular flow path having a liquid inlet and a liquid outlet, a first conduit means in communication with the outlet of said third economizer section and the inlet of said tubular flow path, said tubular flow path being disposed in heat exchange relationship with air flowing through said air conducting means, said air conducting means communicating with the firing means to provide heated air thereto, a second conduit means in communication with the outlet of said tubular flow path and said first economizer section inlet, a third conduit means in communication with the outlet of the first economizer section and the inlet of said second economizer section, and a fourth conduit means in communication with the outlet of said second economizer section and said vapor generator.

6. In a vapor generating apparatus comprising a vapor generator having a setting, a furnace in the setting, means for firing the furnace, said setting having a gas outlet in communication with the furnace and through which gases of combustion flow from the setting, vapor generating surface in the setting in heat exchange relationship with said gases of combustion prior to the flow of said gases from the setting gas outlet, a source of feed liquid, an economizer disposed in said setting beyond said generating surface and in heat exchange relationship with said gases of combustion flowing to said outlet, said economizer comprising a first section, a second section and a third section, said sections being disposed beyond one another respectively in the path of flow of the gases passing to the gas outlet so that the gases pass first over the third section, thence over the second section and thence over the first section, the second and third sections being both connected to said feed liquid source to provide for flow of feed liquid therethrough, an air heater comprising air conducting means through which air flows and a tubular flow path communicating with said third section to receive the feed liquid after passing through said third section to provide flow of liquid through said tubular path, said tubular flow path being disposed in heat exchange relationship with said air conducting means, said air conducting means communicating with said firing means to provide the latter with preheated air, the first section connected to the tubular flow path of said air heater to receive the feed liquid therefrom, means for conducting the feed liquid from said first section to said second section, and means for conducting the feed liquid from said second section to said vapor generator.
